His Attorney.

UNITED STATES PATENT OFFICE

SAMUEL W. MAUGER, OF SCHENECTADY, NEW YORK, ASSIGNOR TO GENERAL ELECTRIC COMPANY, A CORPORATION OF NEW YORK

SAFETY SWITCH

Application filed September 4, 1930. Serial No. 479,730.

The present invention relates to safety switches and more particularly to switches wherein the electrical circuit between switch contacts is completed through one or more fuses.

The matter of replacing fuses or opening circuits by means of fuses is attended by a certain amount of danger to the operator, especially where the voltage is such that an arc may be drawn or where a circuit to ground may be completed through the operator. Furthermore, there is always a danger of fuses blowing in the operator's face, which may result in severe burns to the face and hands or injury to the eyes.

The object of the invention is the provision of a fused safety switch which is simple in structure, low in cost and which provides maximum protection to the operator when opening or closing the switch or when removing or replacing the fuses.

The invention will be more clearly understood if reference is had to the accompanying drawing, of which Fig. 1 is a vertical section parallel to the fuses; Fig. 2 is a similar section at right angles to that of Fig. 1 of a fused switch embodying the invention; Fig. 3 is a view of the operating handle partly in section and showing the means for locking it in place on the switch operating rods, and Fig. 4 is an inner end view of the handle portion shown in Fig. 3.

In order that maximum protection may be provided to the operator, the switch mechanism 5 is mounted on the rear side of an insulating switch board 6 in such a manner that it may be operated only by a person standing in front of the switch board and manually pulling out or pushing in on the handle 7, depending on whether the switch is to be opened or closed.

The door panel 9 of the switch board, mounted just in front of the switch 5 is pivotally held in place as by the spring hinges 11. These hinges are under sufficient tension to maintain the panel in closed position unless it is held or blocked open. As a positive assurance against opening this panel when the switch is in closed position, the switch handle 7 is interlocked with the panel in such

a manner that it must first be removed, which can only be done when the switch 5 is in open position.

Interlocking of the handle 7 with the panel 9 is accomplished by providing the handle with inwardly projecting ends 8, which when the switch 5 is closed, extend into and through apertures 10 cut from the panel 9.

The ends of the handle are recessed to form sockets therein, adapting the handle to be mounted on the outer ends of the switch operating rods 13. It is releasably fastened in place by locking devices 14 in each end of the handle and comprising the latch 15 (Figs. 3 and 4) pivotally held by pin 20 in the longitudinal slots 16 cut or formed in the ends of the handle. The latch is provided, intermediate its ends, with downward projecting V-shaped catches or lugs 17 adapted to seat in similar shaped recesses in the ends of switch operating rods 13.

The inner end of the latch is provided with a circular spring clip 19 which yieldingly slips down over rod 13 when the latch 15 is pushed down into locking position, and holds it releasably in place. As the back or top of the latch 15 falls flush with the upper side of the handle 7. The latch 15 is also provided with an inward extension or thumb piece 21 which the operator grips when he intends to lift it in order to release the handle 7 from the ends of rods 13. But as will be hereinafter explained, releasing of the handle from the switch rods is only possible when the switch is in open position.

The inner ends of the switch operating rods are threaded and extend through a slideable insulating base 22, where they are securely locked in place by suitable nuts. This base is provided with four guide bushings 23 mounted in apertures therethrough which act to guide and hold it in alignment as it is moved back and forth. These bushings slide along four stay or guide rods 24, which are threaded at each end, the left ends being securely clamped to the switch board 6 and angle irons 47 by nuts 25 while the right ends serve to hold and clamp the fixed insulating base or panel 26 to the angle iron supports 100

27, or in a position directly in back of slide-
able base 22.

The fixed base 26 acts as a support for three pairs of blades 28, each pair being held in vertical alignment by annular shoulders 29 and nuts 31 screwed on the rear end of the threaded extensions or studs 30 which pass through apertures in the base. Nuts 31 may be used also to clamp terminal lugs of circuit wires in electrical contact with the rear ends of the blade studs.

Mounted in the slideable base 22 in such a position as to align up with the blades 28 are three pairs of switch jaws 32, formed from suitable strips of spring metal bent to the shape shown and inserted in slots through the base. Sections of angle iron 33 are welded or suitably fastened to the sides of the strips and act to clamp the jaws in place so that when the slideable base 22 is pushed inward the jaws 32 will yieldingly slip over the blades 28 and make good electrical contact therewith.

Each set of jaws are joined electrically through cartridge fuses 34 releasably held in place and connected electrically to the jaws by spring clips 35 which are attached to the forward extension 32a of jaw forming strips 32.

The lock nuts on the switch operating rods 13 are so adjusted that when the switch jaws 32 are over the ends of blades 28 or when the switch is in closed position, the inwardly projecting ends of the handle 7 will project inward through the apertures 10 in the swing-
ing panel 9 thus preventing the lifting of the latch 15 and the detachment of the handle 7 from the ends of the switch operating rods 13. It will be noticed that as long as the handle is held in place on the switch operating rods 13 the panel 9 cannot be opened, thus preventing access to the switch or fuses.

On the other hand when the switch 5 is in open position the inwardly projecting ends of the handle will be free of the switch board or in front of it and the latch members 15 may be lifted, the handle removed from the switch operating rods 13 and the panel 9 swung open, permitting access to the inside of the enclosure in order that the fuses 34 may be removed or replaced.

It will be further observed that when the switch is in open position and the panel 9 swung open, the sliding base 22 acts as a barrier between the operator and the charged blades 28 or if the switch is in closed position the panel 9 acts as a barrier between the fuses and the operator, he being thus always protected from live parts by one or the other of the barriers.

60 What I claim as new and desire to secure by Letters Patent of the United States, is:

1. A fused switch having in combination, a switch board, provided with a swinging panel, a fixed base board disposed rearwardly of said swinging panel, a movable base dis-

posed intermediate said fixed base and swinging panel, means for guiding the said movable base, a plurality of contacts mounted in said movable base and adjacent to said fixed base, removable electrical fuses mounted on the side of said movable base adjacent to said swinging panel and connecting said contacts by pairs, contacts mounted in said fixed base in alignment with said movable contacts, means extending through said swinging panel for reciprocating said movable base, and means for interlocking said swinging panel therewith whereby it may be swung open only when said switch is in open position.

2. A reciprocating switch, a handle for operating said switch, a movable panel disposed intermediate said switch and said handle, a rod connected to the movable part of said switch and projecting through said panel and having said handle mounted on the end of said rod, and a locking means releasably securing said handle to said rod, said means capable of being unlocked only when said switch is in open position.

3. A safety switch comprising an enclosure provided with a movable panel, stationary contacts mounted in said enclosure opposite said panel, a transverse barrier plate movable between said stationary contacts and said panel and provided on the front side with fuse clips and on the rear with switch contacts electrically connected respectively to said fuse clips, rods connected to said barrier and extending toward said panel, and an operating handle for said barrier extending through said panel and locked to said rods while the switch is in closed circuit position and capable of being detached therefrom while in withdrawn open circuit position and permitting the panel to be opened.

In witness whereof I have hereunto set my hand this 3rd day of September, 1930.

SAMUEL W. MAUGER.
